UNITED STATES PATENT OFFICE.

SAMUEL H. LEWIS, OF RICHMOND, VIRGINIA.

STEAM-SUPPLY MEANS FOR LOCOMOTIVE CYLINDERS.

Application filed July 29, 1919. Serial No. 314,101.

To all whom it may concern:

Be it known that I, SAMUEL H. LEWIS, a citizen of the United States, residing at Richmond, in the county of Henrico and State of Virginia, have invented certain new and useful Improvements in Steam-Supply Means for Locomotive Cylinders, of which the following is a specification.

My invention relates to fluid pressure operated apparatus, for supplying steam to the cylinder or cylinders of a railway locomotive, when the main supply of steam is cut off therefrom, and the engine is drifting by gravity or inertia.

As is well known, railway locomotives are frequently operated with superheated steam, which is heated to a temperature of 650°-700° F. This high temperature steam heats the walls of the cylinders of the engine to a high temperature, so that the oil is burned or flashed, upon the introduction of air, smoke box gases and cinders, into the cylinder or cylinders. Thus air, gas and cinders are drawn into the cylinder or cylinders, when the main supply of steam is cut off, and the engine is traveling or drifting above a comparatively low speed, as partial vacuums are then ordinarily created within the cylinders. It is obvious that the intake of air and the like into the cylinders may be prevented by the presence of a suitable amount of steam in such cylinders, when the main supply is cut off and the engine is drifting.

An important object of the invention is to provide automatic means, in no way actuated by vacuums within the cylinders of the locomotive, to supply steam to the cylinders so that vacuums can not be produced therein.

A further object of the invention is to provide automatic means to open the steam valve, which supplies the drifting steam to the cylinders, and retain the same permanently open, during the travel of the locomotive above a predetermined speed, and to cause the steam valve to close when the locomotive slows down to a predetermined speed, and to retain the same closed when the locomotive travels below this speed, or is stationary.

A further object of the invention is to provide means whereby the cylinders of a locomotive will be automatically supplied with steam when the locomotive is drifting

at speeds which would cause the creation of vacuums, and automatically cut off from the supply of steam sufficiently early to permit of the locomotive coming to a stop with no steam remaining in the cylinders. 60

A further object of the invention is to provide means whereby the amount of steam admitted to the cylinders while drifting is varied in accordance with the speed of the locomotive within certain limits. 65

A further object of the invention is to provide apparatus of the above mentioned character, which is of simplified construction, and is adapted to be installed upon railway locomotives of the ordinary type, 70 without materially altering the construction thereof.

Other objects and advantages of the invention will be apparent during the course of the following description.

In the accompanying drawings forming a part of this specification, and in which like numerals are employed to designate like parts throughout the same,

Figure 1 is a side elevation of apparatus 80 embodying my invention, showing the same applied to a railway locomotive,

Figure 2 is an enlarged central vertical sectional view through the control apparatus, parts being shown in elevation, 85

Figure 3 is an edge elevation of the body portion of the control apparatus, taken at a right angle, to Figure 2, with parts omitted;

Figure 4 is a horizontal sectional view, 90 taken on line 4-4 of Figure 3, with parts omitted;

Figure 5 is a central vertical sectional view through a steam valve and associated means, parts in elevation;

Figure 6 is a view similar to Figure 5, 95 and the valve being elevated to contact the disk; and

Figure 7 is an enlarged fragmentary sectional view illustrating the use of different size spacing rings and washers and showing the valve in fully elevated position.

In the drawings, wherein for the purpose of illustration is shown a preferred embodiment of my invention, the numeral 10 designates a railway locomotive of any well known or preferred type. This locomotive embodies a steam turret 11, as shown. The numeral 12 designates the cylinders of the locomotive, each of which is provided 110

with the usual steam chest 13, for connection with a steam supply pipe 14. There are two steam supply pipes 14, one for each cylinder, as is well known, which are connected with the superheater. The steam chest 13 has the usual distribution valve operated by a radius rod 15 or the like.

Attention being called more particularly to Figures 1, 2, 3 and 4, it will be seen that 10 the numeral 16 designates a control apparatus, as a whole, comprising a pressure chamber 17, which is preferably cylindrical, and vertically arranged. The control apparatus is rigidly connected with a horizontal arm 18, which is rigidly secured to a bracket 19, attached to the guide yoke of the locomotive or other suitable part thereof.

The numeral 23 designates a partition or 20 wall, forming a chamber 24 having at its upper end a vertical opening 25, in communication with a pressure supply pipe 26, as shown. This pressure supply pipe 26 leads to a tank 27, containing compressed air 25 or other fluid pressure. At its lower end, the chamber 24 has communication with the chamber 17, through the medium of a vertical port 28. At the upper end of the port 28 is a valve seat 29, engaged by a vertically 30 movable valve 30, carried by a vertical depending stem 31. This stem projects through a depending guide tube 32 and a stuffing box 33. A sliding sleeve 34 is apertured for the reception of the stem 31 and is arranged within the lower end of guide tube 32. The lower portion of the stem 31 has a transverse opening for the reception of a pin 35, contacting with the sliding sleeve 34. A compressible coil spring 36 surrounds the 40 stem 31 and is confined between the end of the sleeve 34 and a gland 37, projecting into the stuffing box 33.

Arranged within the lower portion of the chamber 17 is a raised portion 38, having a vertical port 39, in communication with a receiver pipe 40, as shown. At the upper end of the port 39 is a valve seat 41, engaged by a vertically movable valve 42, secured to a depending vertical valve stem 43. This 50 valve stem extends through a tubular guide 44, and stuffing box 45. Surrounding the lower portion of the stem 43 is a sliding sleeve 46, mounted to reciprocate within the lower portion of the tubular guide 44. The lower end of the stem 43 has a transverse opening formed therein for the reception of a pin 47, as shown. A compressible coil spring 48 surrounds a portion of the stem 43, and is confined between the sleeve 46 and a gland 49.

Means are provided to alternately raise the stems 31 and 43, for opening the valves carried thereby, such means comprising a swinging arm 50, provided at its upper end 65 with a head 51, having an opening 52 formed

therein, to pivotally receive a pin 53. This pin is carried by depending supports 54, rigidly secured to the lower end of the depending tubular guides. At its upper end, the swinging arm 50 is provided with lateral 70 extensions 55, having screw-threaded openings for the reception of set screws 56 or the like. When the arm 50 is in the vertical position, the screws 56 are both slightly spaced from the lower ends of the valve 75 stems, whereby both valves are closed, and when the arm 50 is swung in either direction the corresponding valve stem is elevated and the valve unseated. However, both valves cannot be open at the same time.

Pivotedly connected with the lower end of the arm 50 is a link 57, which is pivoted to the radius rod 15, or other movable part of the locomotive.

The receiver pipe 40 which leads into the 85 vertical port 39 is also connected with fluid pressure operated apparatus, comprising a vertical cylinder 58, provided near its upper end with a port 59, leading to the atmosphere. Mounted to reciprocate within the 90 cylinder 58 is an ordinary movable piston 60. This piston fits within the cylinder 58 in a manner to permit of the slight escape of fluid pressure between it and the wall of the cylinder, whereby this fluid pressure may pass 95 to the atmosphere through the port 59, but the escape of fluid pressure is not sufficient to prevent the fluid pressure introduced into the lower end of the cylinder 58 from elevating the piston 60, in the proper operation 100 of the apparatus. The piston 60 has a vertical stem 61 connected therewith. The volume of the receiver pipe 40 and cylinder 58 is suitably proportioned to the volume of the chamber 17, whereby the valves 30 and 42 105 are preferably open a number of times before the pressure in the receiver pipe is sufficient to raise the piston for opening the stem valve, to be described. Further, the valves 30 and 42 must be alternately opened with 110 sufficient speed to overcome the loss of pressure due to leakage through the port 59 to the atmosphere, and maintain a pressure sufficiently high to hold the piston elevated. It is thus seen that the piston will be elevated 115 and retained elevated, when the speed of the locomotive exceeds a predetermined degree, whereby the steam supply valve is retained permanently open during such operation.

The numeral 62 designates a drifting supply pipe, the forward end of which is connected with branch pipes 63, by means of a T-coupling 64. These branch pipes lead into the steam supply pipes 14. It is to be understood that the invention is in no sense restricted to this precise construction, as it is obvious that the forward end of the pipe 62 may be connected in the steam passage between the main throttle valve and the loco- 130

5 motive cylinders. The pipe 62 has its opposite end suitably connected with the steam turret 11, but it is to be understood that this pipe may be connected with any other suitable source of steam supply.

Connected in the pipe 62 is a valve structure including the casing 65, provided with a valve seat 66, having its opening covered and uncovered by a vertically movable valve 67 carried by the stem 61. The valve 67 is moved downwardly by a compressible coil spring 68 and also by the fluid pressure upon the unbalanced area of the upper end of the valve stem 61, to which the valve 67 is 10 rigidly secured. The stem 61 operates within a guide 69. Any steam passing from the casing 65 about the stem 61 through the guide 69, discharges to the atmosphere through the port 59.

20 An opening 70 is formed in the casing 65 directly above and axially aligned with the valve 67. This opening is provided with screw threads to receive the threaded lower end of a sleeve 71. The sleeve 71 is provided at its lower end with an internal shoulder 71^a forming a reduced bore 72 adapted to slidably receive an upper extension 72^a of the valve 67. It will be noted by examination of Figure 5 that the upper 25 end of the extension 72^a of the valve is even with the shoulder 71^a of the sleeve 71 when the valve is seated. The main bore of the sleeve is provided with internal threads 73 adapted to receive an externally threaded 30 tubular cap 74. Seated upon the shoulder 71^a of the sleeve is a spacing ring 75 upon which is placed a disk 76. Mounted in the tubular cap 74 and extending between the interior of the upper end thereof is a compression spring 77. Between the upper end 35 of the sleeve 71 and the shoulder 78 of tubular cap is interposed a washer 79. It will be obvious that by varying the thickness of the spacing ring 75 the extent of the initial opening of the valve 67 may be 40 varied and by varying the thickness of the disk 76 or washer 79 the compression of the spring 77 may be varied thereby making adjustable the degree of pressure necessary 45 in the cylinder 58 to cause the piston to move the valve to its fully opened position. The washer 79 may be omitted if desired.

By means of the construction disclosed, 50 the tension of spring 77 does not oppose the opening of the valve until the valve has been initially opened a predetermined distance. In some instances, the valve sticks to the valve seat and it requires more force 55 to move it a given distance from the valve seat than is required to move it a similar distance after being initially opened.

The operation of the apparatus is as follows:

60 When the locomotive is traveling with the

main throttle, valve partly or wholly open the steam is supplied to the cylinders 12 through the steam pipes 14, as is well known. The reciprocatory movement of the rod 15 swings the arm 50 to alternately open one 70 valve 30 and close the other valve 42. When the rear valve 30 is open, compressed air passes from the tank 27 through pipe 26 into the pressure chamber 17, but can not pass therefrom as the forward valve 42 75 is closed. When the forward valve 42 is open the rear valve 30 is closed, whereby the fluid pressure within the chamber 17 discharges into the receiver pipe 40 and the lower end of the cylinder 58. This introduction of pressure within the cylinder 58, when it rises to a required degree, causes the piston 60 to raise, thereby opening the valve 67. The fluid pressure can slightly escape around the piston 60, but the pressure is intermittently supplied from the chamber 17, sufficiently rapid when the locomotive is traveling at a predetermined speed, to elevate the piston until the upper extension thereof contacts the disk 76 and 80 to retain the piston elevated and the valve 67 partially open as shown in Figure 6, and a small quantity of the steam from the turret 11 passing through the pipe 62 will discharge into the steam pipes 14, and hence 85 into the cylinders 12. As the speed of the locomotive increases the pressure in the cylinder 58 increases and when this pressure reaches a predetermined degree the valve 90 is fully opened against the action of the 100 springs 68 and 77. The steam is fed through the pipe 62 into the cylinders 12 when the throttle is closed, in proper amounts to prevent the formation of vacuum therein. This prevention of the formation of vacuum 105 within the cylinders and the exclusion of air and the like therefrom prevents the destruction of the lubricant. The steam also serves to lubricate the cylinders. Particular attention is called to the fact that the opening or closing of the valve 67 is in no way dependent upon the creation of vacuum 110 within the cylinders, as by the employment of my apparatus, it is impossible for vacuums to occur.

When the speed of the locomotive becomes lower than is required to maintain fluid pressure in the receiver pipe 40 and cylinder 58 at the degree required to hold piston 60 and valve 67 elevated against the action of 120 the spring 77, the piston 60 will be forced downward by the combined action of the springs 77 and 68 and the action of the steam upon the unbalanced area of the upper end of the valve stem 61. Further reduction of the speed of the locomotive will further reduce pressure in the cylinder 58 and the piston will be forced still further downwardly by the spring 68 and the action 125 of the steam upon the unbalanced area of 130

the upper end of the valve stem 61 and the valve 67 will be closed. This cuts off the supply of steam through the pipe 62 to the cylinders. When the locomotive comes to a stop, one or both of the valves 30 and 42 are closed, thereby entirely cutting off supply of fluid pressure to the cylinder 58 beneath the piston 60.

It will readily be seen that the amount of pressure supplied to the cylinder 58 is directly proportional to the speed of the locomotive and therefore the valve 67 partially opens at a given speed, fully opens at a predetermined higher speed, partially closes if the speed of the locomotive drops below this higher speed and fully closes below the speed set for the initial opening, all of these actions being automatic.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. In apparatus for supplying steam to the cylinders of a locomotive while moving, a fluid pressure motor having a slow leak therein, said motor being free from communication with the cylinders of the locomotive, means for supplying fluid under pressure to said motor in amounts varying directly with the speed of the locomotive, a steam supply conduit, a valve in said conduit adapted to be opened by the motor when the speed of the locomotive exceeds a predetermined speed, and means for regulating the initial opening of the valve.

2. In apparatus for supplying steam to the cylinders of a locomotive while moving, a fluid pressure motor having a slow leak therein, said motor being free from communication with the cylinders of the locomotive, means operated by the fluid pressure motor to supply steam to the cylinders, a pressure chamber to supply fluid under pressure to the motor and connected at all times therewith, means to control the inlet and outlet of fluid to and from the chamber, said control means having positive connection with a movable part of the engine to be operated in unison therewith, said motor being adapted to be set in action when the speed of the locomotive reaches a predetermined point, and means for varying the amount of steam delivered to the cylinders at any given speed above such predetermined point.

3. In apparatus of the character described, a conduit to supply steam to the cylinders of a locomotive, a valve to control the passage of steam through the conduit, a pressure

chamber, an inlet valve for the pressure chamber, an outlet valve for the pressure chamber, pressure operated means connected with the valve in the conduit to operate it, said pressure operated means communicating with the pressure chamber upon the opening of the outlet valve and being adapted to be actuated when the pressure therein reaches a predetermined amount, means for yieldingly limiting the initial opening of said valve, and a movable member adapted to alternately open the inlet and outlet valves of the pressure chamber, said member being connected with a movable part of the locomotive.

4. In apparatus of the character described, a conduit to supply steam to the cylinders of a locomotive, a valve to control the passage of steam through the conduit, pressure operated means connected with said valve and adapted to operate it, means for supplying fluid under pressure to said motor in amounts varying directly with the speed of the locomotive, means for yieldingly limiting the initial opening of said valve, and additional means for limiting further opening of said valve.

5. In a device of the character described, a conduit for supplying steam to the cylinders of a locomotive, a valve arranged in said conduit, pressure operated means to control the opening of said valve, means for supplying fluid under pressure to said pressure operated means, said means being connected to a movable part of the locomotive, said pressure operated means comprising a cylinder having an opening to permit slow exhaust, a piston arranged in said cylinder, said piston being provided with a piston rod connected to said valve, a spring arranged in said cylinder and engaging said piston to normally maintain the piston in inoperative position, means whereby the valve may be opened a predetermined amount against the tension of said spring by the pressure in said cylinder, and additional means to yieldingly retard further opening of said valve.

6. In apparatus for supplying steam to the cylinders of a locomotive while in motion, a steam supply conduit, a valve to control the passage of steam through the conduit, a pressure operated motor to actuate said valve, said motor including a piston connected to said valve, means for supplying fluid under pressure to said motor, said means being connected to a movable part of the locomotive, a spring engaging said piston to maintain said valve in a closed position when the pressure in said cylinder is below a predetermined amount, a hollow sleeve arranged above said valve and in axial alignment therewith, said valve being provided with an extension extending into said sleeve, a spacing ring arranged at the

bottom of said sleeve, said ring being provided with an opening through which the extension passes when the valve is opened, a plate arranged above said spacing ring and adapted to engage said extension when the valve is open, and a spring arranged above said plate.

In testimony whereof I affix my signature in presence of two witnesses.

SAMUEL H. LEWIS.
